AIRPLANE

Thomas Gardner Hill, Atlanta, Ga., assignor to Lockheed
Aircraft Corporation, Burbank, Calif.

Filed Dec. 30, 1966, Ser. No. 5,247

Term of patent 14 years

(Cl. D71—1)

FIG. 1

Fig. 2

FIG. 3

FIG. 4

FIGURE 1 is a perspective view taken from the top front of an airplane embodying my present design;

FIGURE 2 is a bottom plan view thereof;

FIGURE 3 is a side elevation thereof; and

FIGURE 4 is a front elevation thereof.

The dominant features of my design reside in the portions shown in full lines.

I claim:

The ornamental design for an airplane, substantially as shown and described.
